UNITED STATES PATENT OFFICE

HENRY ELLIOTT, OF HILLHEAD, GLASGOW, SCOTLAND

LATCH DEVICE

Application filed September 1, 1928, Serial No. 303,554, and in Great Britain September 19, 1927.

This invention has reference to latches and latch fittings for windows and the like and particularly to latches or fittings of the type having a retaining bolt and a trigger bolt in combination with a plate having holes therein and means to engage with the trigger bolt when the window or the like is partly opened or closed. Such co-operation with the trigger bolt releases the retaining bolt which enters a hole in the plate and thereby prevents further opening of the window or the like until the retaining bolt has been manually withdrawn.

My invention has for its object to provide an improved and simplified latch which will be cheap to manufacture, and sensitive and positive in its operation.

Another object of my invention is to provide an improved plate with holes therein and trip to co-operate with the trigger bolt.

A still further object of my invention is to prevent unauthorized interference with the latch and thereby prevent the window or the like being opened by intending intruders.

In order that my invention will be properly understood I have hereunto appended three explanatory sheets of drawings illustrating preferred constructions of latch fittings in accordance with my invention and their application to windows and whereon:—

Figure 1 illustrates latch fittings in accordance with my invention as applied to a window of the sliding sash type, the window being shown closed and secured.

Figure 2 is an end elevation of said fittings.

Figure 3 is a view similar to Figure 2 but showing the window partly open and secured.

Figure 4 is a plan view of Figure 1.

Figure 5 is a plan view of the latch with cover shown in section and the retaining bolt in the operative or securing position.

Figure 6 is a view similar to Figure 5 but showing the retaining bolt in an inoperative position.

Figure 7 is an end elevation of Figure 6 and

Figure 8 a plan view of Figure 5, the casting in said figures being shown in section.

Figure 9 illustrates the improved fittings as applied to a window of the casement type.

Figure 10 is a plan view thereof, the window being shown in two open positions by the dotted lines.

Figure 11 is a perspective view of the latch fittings as applied to a window of the casement type.

Figure 12 is a perspective view of the trip used in combination with my improved latch as applied to a window of the casement type.

Figures 13 and 14 illustrate an inverted plan view of a modified type of latch in accordance with my invention, the base of the casing being omitted.

Figure 15 illustrates in perspective a somewhat modified latch applied to a window having joggles.

Referring to the drawings:—

a is the sliding retaining bolt, *b* the sliding trigger bolt and *c* a pivoted rocking member all housed within a casing *d*.

The retaining bolt *a* is recessed at *a*¹ to form an abutment *a*² which engages an angled arm *c*¹ of the rocking member as indicated clearly in Figures 5 and 6. Said bolt carries a pin *e* having a ring end which encloses a pin *e*¹, which latter is encircled by the helical spring *e*². Said spring, by acting on the head of the pin *e* tends to force the retaining bolt into its outer or operative position as clearly shown in Figure 5.

The sliding trigger bolt *b* is provided with a V like end and is further provided with two laterally turned notched abutments *b*¹ *b*².

The rocking plate *c* is pivoted at *c*² to the back of the casing *d* and in addition to the angled arm *c*¹ is provided with three cam like fingers *c*³ *c*⁴ and *c*⁵. A cord or the like *f*, Figures 1, 2 and 3, is secured to the end of the arm *c*¹ which passes through a slit in the side of the casing *d*.

Reference will now be made to the fittings as applied to a window of the sliding sash type and illustrated in Figures 1 to 4.

As applied to windows of the sliding sash type said latch is secured to the lower sash of the window while to the side of the upper sash is secured a plate *g* having two holes *h* *h*¹ cut therein, said holes corresponding to and registering with recesses cut in the upper sash. To the side of said plate is secured a

trip or abutment forming two oppositely inclined faces j j^1 which make an angle preferably greater than a right angle to each other. Said plate is provided with a longitudinally extending lip or bead g^1 .

5 In operation, when both sashes are in the closed position the sliding retaining bolt a is normally in the forward position and fitting into the recess h in the plate g and corresponding hole in the upper sash by which means both the upper and lower sashes are secured.

10 Should it be desired to either raise the lower sash or lower the upper sash the cord 15 or the like f is pulled. This results in the rocking member c being turned about its pivot c^2 and, by reason of the angled arm c^1 bearing on the abutment a^2 the retaining bolt is drawn inwardly against the action of the 20 spring e^2 .

25 When the retaining bolt is fully withdrawn the angled edge of arm c^1 by bearing on the said abutment a^2 retains the retaining bolt in such position against the action of the spring e^2 , see Figure 6.

30 During said movement of the retaining member the cam like finger c^4 engages with the laterally extending projection b^1 and thereby moves the trigger bolt outwards into the position shown in Figure 6.

35 The lower sash can now be raised or the upper sash lowered, either of said movements resulting in the inclined face j abutting against the trigger bolt b which is consequently forced inwards. In doing so the abutment b^2 bears against the finger c^5 and thereby imparts a partial rotary movement to the rocking member about its pivot which results in the angled edge of the arm c^1 being 40 moved sufficient to permit of the retaining bolt being moved outwards under the action of the spring e^2 .

45 On either of the windows being opened further the retaining bolt shoots into the hole h^1 provided in the plate g and corresponding recess in the sash of the upper frame thereby effectively preventing any further movement of the two sashes relative to each other.

To close the window the cord or the like f 50 is again pulled to withdraw the retaining bolt and move forward the trigger bolt and, on the window being closed, the trigger bolt bears on the inclined face j^1 so that the retaining bolt again shoots forward and shoots 55 into the lower hole h and corresponding recess in the upper window sash when in alignment therewith, thereby securing the window. Thus if the window is closed it is automatically secured and if opened it is automatically secured when the retaining bolt 60 registers with the hole h^1 .

65 If desired the underside outer end of the retaining bolt may be bevelled or angled so that, when in engagement with the upper hole h^1 , it will be automatically moved in to

its inoperative position on either the upper or lower sash being moved to close the window.

70 Finger c^3 prevents the trigger bolt slipping out and further ensures that it is kept in the relative position to its rocking plate.

75 If desired a second trip or inclined face arranged to co-operate with the trigger bolt may be located at a level higher than the opening h^1 , so that, should the retaining bolt be withdrawn from said hole h^1 and the window further opened the retaining bolt is again released. When opened to such extent, however, it will be apparent to the eye that 80 the window is opened to too great an extent to be safe against unauthorized intruders and whenever the window is closed to what may be regarded as a safe extent the retaining bolt again shoots into hole h^1 and prevents further opening of the window.

85 The lip or bead g^1 serves to prevent a knife or other tool inserted between the glass of the lower sash and the lower rail of the upper sash from being introduced between the end of the retaining bolt and the plate g as to interfere with the functioning of the latch.

90 By reason of both the retaining bolt and the trigger being arranged to slide as herein set forth a securing device of very compact, simple and strong construction is obtained.

95 The securing device may be applied to windows of the casement type and also to doors, fanlights and the like. In Figures 9 to 12 the securing device is shown applied to a casement window. In said figures the latch is exactly similar to that set forth for use in windows of the sliding sash type but the co-operating trip is slightly modified. In 100 said figures the latch is shown applied to the window frame while the trip is applied to the hinged sash, but the arrangement may be reversed.

105 On the upper batten of the casement window is secured a horizontal plate s which may be formed integral with a vertical plate s^1 .

110 Plate s is provided with two oppositely inclined faces t t^1 and also with an opening u which registers with a corresponding recess formed in the top of the batten.

115 When the window is closed the retaining bolt bears against or is directly in front of the upper batten and thereby prevents the window being opened.

120 On the cord or the like f being pulled the retaining bolt is withdrawn clear of the door while the trigger bolt is moved in front of the inclined face t^1 .

125 On the window being opened said inclined face actuates the trigger bolt which, as previously explained, releases the retaining bolt which drops into the hole u thereby securing the window in a partly open position.

130 To open the window further the retaining bolt is withdrawn and the trigger moved outwards, the inclined face t permitting of such

movement. The window can then be opened to any further extent found desirable.

On closing the window the inclined face *t* co-operates with the trigger bolt so that the retaining bolt is again released to move forward under the action of its spring but the hole *u* is so positioned with respect to the inclined face *t* that the bolt cannot drop into the hole *h* but bears on the plate *s* until the window is fully closed when it moves into its securing position in front of the top batten.

The front plate *s*¹ prevents the insertion of a tool to interfere with the retaining bolt when the window is partly opened and locked.

The latch may be somewhat modified as shown in Figures 13 and 14 wherein the retaining bolt *a* is loaded by helical spring *n* and trigger bolt *b* by helical spring *p* and the rocking member *c* is provided with two limbs *o* *o*¹. The operating cord *f* is attached to the retaining bolt, the inner end of which is bent over and the bent over end *a*¹ recessed or notched as indicated at *o*² to receive the limb *o*¹. The other limb *o* is provided with cam like face *g* with which the inner end of the trigger bolt *b* co-operates.

The pin *q*¹ carried by the trigger bolt *b* is arranged to bear against the pin *q*² carried by the rocking member when said bolt is in its outer position, the spring *p* tending to tilt the rocking member.

In Figure 13 both of the bolts are shown in the forward position.

On pulling the operating cord the retaining bolt is withdrawn until the notched end thereof clears the end of the limb *o*¹ thereby releasing the said limb *o*¹ which is then tilted by the action of the spring *p*, moving to a position under the notched bent over end *a*¹ of the retaining bolt, thereby holding the bolt in its inoperative position.

On the window being moved so that the trigger bolt co-operates with a trip said bolt is moved inwards and its inner end co-operates with the cam like faces *g* of the rocking member thereby tilting the latter so that the limb *o*¹ registers with the notch of the bent over end of the retaining bolt *a* thereby permitting said bolt to shoot forward under the action of the spring *n*. Such construction of latch may be still further modified by providing a notch *s* in the limb *o*¹ which recess receives the notched end of the retaining bolt when the latter is in its closed position.

Before the retaining bolt can be withdrawn it is necessary that the rocking member should be tilted so that said notch is clear of the trigger bolt this being conveniently effected by means of a cord or the like *r* attached to the rocking member. When this is done the operating cord can be pulled to withdraw the retaining bolt. By such modification two distinct operations are necessary to withdraw the retaining

bolt thereby rendering tampering with the fittings from the outside a more difficult operation.

It will be noted that two notches *s* are provided in the limb *o*¹ the arrangement being such that if the retaining bolt is not permitted to shoot home to the full extent the second notch will operate to engage the retaining bolt.

If desired a key operated lock may be provided to positively lock the latch fittings in the securing position.

In Figure 15 the lower sash is provided with a joggle *v* which would prevent the application thereto of a latch fitting as illustrated in Figures 5 to 8. For such windows the latch fitting is modified by shortening the bent arm *c*¹ and providing a short arm *v*² rigidly secured to the pivot pin *c*² to which the rocking member is also rigidly secured.

The operating cord *f* is secured to the arm *v*² and the latch operated as herein described.

It will be noted that there is no projecting arm which will foul the joggle *v*.

What I claim is:

1. For securing windows and the like a latch comprising a casing, a longitudinally sliding retaining bolt and a longitudinally sliding trigger bolt, both located in said casing, a rocking member pivoted to the casing and arranged to co-operate with said two bolts and means to withdraw said retaining bolt to an inoperative position or non-securing position, and retain it in such position until the trigger bolt is actuated, in combination with a plate provided with holes therein, and a trip comprising two oppositely inclined faces adapted to co-operate with the trigger bolt and to move same longitudinally when the retaining bolt is in an inoperative position, so that the latter is moved longitudinally into an operative position to engage one of the holes in said plate.

2. A latch for windows and the like comprising a casing, a longitudinally sliding spring loaded retaining bolt and a longitudinally sliding trigger bolt both located within the casing, a pivoted rocking member, said member having an arm arranged to co-operate with the retaining bolt and a finger arranged to co-operate with the trigger bolt, and manually operable means to rock said member, the said finger, when the member is so rocked, ejecting the trigger bolt and the arm retracting the retaining bolt and holding same in its retracted position until the rocking member is operated by the trigger bolt co-operating with said finger.

3. A latch for windows and the like comprising a casing, a sliding spring loaded retaining bolt provided with a shoulder, a sliding trigger bolt having a pair of lugs, both bolts being located within the casing between said bolts, said member having an arm

arranged to co-operate with the shoulder and three fingers to co-operate with the two lugs, and manually operable means to rock said member, one of the said fingers, when the member is so operated, co-operating with one of the lugs and ejecting the trigger bolt and the arm co-operating with the shoulder and retracting the retaining bolt and holding it in its retracted position until the rocking member is operated by one of the fingers co-operating with a lug.

HENRY ELLIOTT.
